[57] CLAIM

The ornamental design for a perpetual calendar, as shown and described.

DESCRIPTION

FIG. 1 is a top perspective view of a perpetual calendar showing my new design;

FIG. 2 is a top perspective view thereof, shown with the card portion partially displaced for clarity of illustration only;

FIG. 3 is a front elevational view thereof;

FIG. 4 is a rear elevational view thereof;

FIG. 5 is a cross-sectional view taken along line 5—5 of FIG. 3, with the sectional dimensions shown on an enlarged scale; and

FIG. 6 is a front elevational view of a second embodiment of FIG. 1, the only difference residing in the notched features.

FIG. 2

FIG. 1

FIG. 4

FIG. 5

FIG. 3

FIG. 6
